UNITED STATES PATENT OFFICE.

LEOPOLD GRATHWOL, OF TROY, NEW YORK.

TOBACCO-REFINING VAT.

SPECIFICATION forming part of Letters Patent No. 379,391, dated March 13, 1888.

Application filed March 16, 1887. Serial No. 231,086. (No model.)

To all whom it may concern:

Be it known that I, LEOPOLD GRATHWOL, a resident of the city of Troy, in the county of Rensselaer and State of New York, have 5 invented certain new and useful Improvements in Tobacco-Refining Vats; and I do hereby declare that the following is a full, clear, and exact description of the invention, that will enable others skilled in the art to which it 10 appertains to make and use the same, reference being had to the accompanying drawings, and to the letters of reference marked thereon, which form a part of this specification.

Similar letters refer to similar parts in the 15 several figures therein.

My invention relates to improvements in tobacco - refining vats; and it consists of the novel construction and combination of parts, hereinafter described, and pointed out in the 20 claim.

The objects of the invention are fully set forth in connection with the following description:

Figure 1 of the drawings is a side elevation of the vat. Fig. 2 is a central vertical section of a vat filled with tobacco, taken on the broken line X X in Fig. 3. Fig. 3 is a top plan view of the filled vat with the cover removed.

It is well known to those skilled in the preparation of leaf-tobacco for use in the manufacture of cigars that the natural leaf contains a germ deposit, the presence of which not only acts to retard the combustion of cigars but gives the cigar a very unpleasant flavor. To remove this deposit it has been the practice heretofore to subject the tobacco while in the leaf to what is known as the "sweating process," during which the moistened 35 leaves are permitted to lie in heaps for several days to dissolve the gum. This process involves considerable delay and space for sweating - rooms and necessitates carrying a large stock of tobacco. The individual leaves and bunches of leaves in a given quantity of tobacco being thus treated are differently acted upon according to their location in the heap, which renders it impossible to manufacture 45 a uniform product.

In treating the leaf-tobacco to remove the

germs, I make use of a tank or vat, A, supported by the legs B and provided with a cover, C. Secured to the bottom of the vat is a shallow water reservoir or boiler, D, extending over the greater part of the surface 55 of the vat - bottom. The boiler is provided with ducts a, in any desired number, leading from the interior of the boiler exteriorly to the atmosphere at points above the top of the boiler.

The method of operation is as follows: The boiler is filled with water, which can be introduced through any one or more of the ducts a and be maintained at a uniform temperature of about 212°, or the temperature of boiling water. Any excess of temperature is carried off in the steam, which finds a free exit through the ducts a to the atmosphere or other condensing medium. The bunches of tobacco having been first moistened or soaked 65 in water are inserted in the vat with the stems down, as shown in Figs. 2 and 3. The cover C may then be put on, heat maintained under the boiler, and the tobacco allowed to cook for a short time until the gum is dissolved and runs down the stems to the bottom 70 of the vat.

The entire operation after the water is heated only occupies about half an hour.

When desired, a damp cloth or other absorbent, H, can be laid upon the bottom of the vat before the tobacco is inserted to absorb the gum and prevent its accumulation upon the bottom of the vat.

To prevent the sides or vertical walls of the 85 vat from becoming overheated, I surround them exteriorly near the bottom of the vat with a water-reservoir, E, having an inlet, b, and an outlet, d. This reservoir is filled with cool water, as desired, to prevent overheating 90 the walls of the vat from conduction. The water can be renewed at intervals, as desired, or a constant flow can be maintained in at b and out at d, or vice versa.

The vat may be provided with handles A' 95 for convenience of transportation.

The boiler may have a faucet, F, for drawing the water therefrom.

Instead of the lamp G any of the well-known means of heating may be employed.

What I claim as new, and desire to secure by Letters Patent, is—

In a tobacco-refining vat, the combination of a steam-tight tank, a subjacent open boiler, 5 and a cold-water reservoir, the latter surrounding the tank near its lower end, substantially as shown and described.

In testimony whereof I have hereunto set my hand this 7th day of March, 1887.

LEOPOLD GRATHWOL.
